[57] ABSTRACT

[21] Appl. No.: 6,815

In a single capstan two-vacuum chamber web transport, the web (tape) is vacuum urged into the chambers. The web has a tendency to slip over the capstan such that one chamber receives all of the tape to the exclusion of the other. This undesired action is prevented by providing fluid communication means extending between the two chambers with no other fluid communication connections. As the web enters one chamber, it is clamped to the fluid communication means by the vacuum applied through the other chamber. Movement of the web over the capstan is then inhibited, and the web loads into the other chamber. When the web is in both chambers, the fluid communication means is sealed off by the web making it inoperative.

SELF-VALVING WEB LOADING AND TRANSPORTATION

BACKGROUND OF THE INVENTION

This invention relates to web transport and, more particularly, to apparatus which facilitates loading a web into vacuum chambers (for example of the type included in Patent Office classification 242-182).

In present day single capstan magnetic tape handlers or drives, reliance is placed upon the wrap of the tape around the capstan and the pull of the vacuum in the adjacent vacuum columns or storage chambers to prevent the tape from slipping over the capstan. While loading the tape, vacuum is applied to the chambers and the storage reel brakes are released to allow the tape to be drawn into the vacuum chambers. At this time, the web or tape can easily load into one column first to the exclusion of the other column. That is, in loading, the web extends between two supply spools over the web-receiving openings in the chambers. The spools are freed for rotation to permit web unspooling into the chambers. The frictional engagement of the capstan with the web is relied upon to prevent the web from a spool to move past the opening of an adjacent chamber over the capstan and thence into the chamber receiving web from the other spool. When this happens, no part of the web enters the adjacent chamber. This undesired action is caused by the tape slipping over the capstan (i.e., the wrap of the web on the capstan is insufficient to prevent it from slipping thereover). With the reel brakes released, no tension is applied to the tape resulting in a low frictional engagement with the capstan. If the tape or web loads into one chamber to the exclusion of the other, not only is there possible tape damage, but human intervention is required to restore normal operation. Ideally, the web loads equally into both vacuum chambers; however, due to variations in the web caused by extended storage in tape libraries, creased tape, friction, and unexplainable friction in the tape path between the spools and the chambers, the tape or web sometimes will load into one chamber and not load into the other. In data processing operations, this is called "tape dump" requiring manual intervention. The web will not enter a second vacuum chamber because it then extends over the opening of the chamber with the vacuum or fluid flow in the chamber insufficient to cause it to load into such chamber.

SUMMARY OF THE INVENTION

It is an object of this invention to provide a web-handling device which loads a web into two web-receiving vacuum chambers in a manner that the web is not loaded entirely into one chamber to the exclusion of the other chamber.

Apparatus using the present invention includes a pair of vacuum chambers, preferably in a side-by-side relationship. Each chamber has a web-receiving opening at the same end of a common wall separating the chambers. A web-moving capstan is rotatably disposed on that same end of the wall between the openings. Fluid communication means extend between the chambers immediately below the capstan such that the vacuum in the two chambers is exchanged through such fluid communication means. When loading a web, when the web first enters the first chamber, the web is clamped to the fluid communication means by the vacuum from the other chamber. The web then cannot slide over the capstan into the first chamber. The web then proceeds to load into both chambers. When the web is covering both ends of the fluid communication means in the respective chambers, the fluid communication means is inoperative to affect web motion. In the illustrated embodiment, the fluid communication means has a dimension less than the thickness of the wall, which corresponds to the width of the web being handled. In one preferred embodiment, fluid communication means comprises a plurality of apertures extending through the wall. The apertures are preferably chamfered at the end to prevent web wear. In another embodiment, the fluid communication means comprises a slot formed in the front side of the common wall

between the chambers. The fluid communication means is completed by a door, which is movable against the front face of the wall to close the slot to form a channel between the two web-receiving chambers. It is preferred that a common vacuum source provide vacuum to both of the web-receiving chambers.

The foregoing and other objects, features, and advantages of the invention will be apparent from the following more particular description of preferred embodiments of the invention, as illustrated in the accompanying drawings.

DESCRIPTION OF THE DRAWINGS

FIG. 1 is a simplified diagrammatic front cross-sectional view of an apparatus incorporating the teachings of the present invention.

FIG. 2 is a simplified cross-sectional diagrammatic view of a slot-type of fluid communication means usable with the FIG. 1 illustrated apparatus.

FIG. 3 is a simplified diagrammatic representation of another fluid communication means comprising a single hole extending through a wall and usable with the FIG. 1 illustrated apparatus.

DETAILED DESCRIPTION

With particular reference to the drawings, like numbers indicate like parts and structural features in the three views. In FIG. 1, a pair of tape or web supply spools 10 and 11 are disposed on opposite sides of the pair of web-receiving vacuum chambers 13 and 14. Common wall 15 is intermediate the web-receiving chambers and forms one side of each chamber. Rotatably disposed on the upper end of wall 15 is web-driving capstan 16 used to transport web 19 between web-receiving chambers 13 and 14. Common wall 15 has web contacting surfaces in the chambers. Vacuum source 17 is in fluid communicative relationship to common plenum 18 which forms the bottom portion of web receiving chambers 13 and 14. In operation, source 17 provides an equal vacuum to both chambers 13 and 14 such that web 19 has an equal force exerted thereon at the web receiving openings 20 and 21 of the chambers. The width of web 19 approximates the depth of chambers 13 and 14 and, hence, the width of web-contacting surfaces 46 and 47, as measured perpendicular to the face of the drawing.

To load web 19 into chambers 13 and 14, web 19 is moved across the outside of openings 20, 21, and across capstan 16, as indicated by dotted line 25. The motors or brakes of spools 10 and 12 are released such that web 19 is free to unreel from both spools. Vacuum spool 17 is activated to provide a vacuum in both chambers 13 and 14. The resulting pressure differential across web 19 urges it downwardly into chambers 13 and 14, as is well known. In prior web handling devices, the wrap of web 19 on the friction surface of capstan 16 was relied upon to prevent the web from moving thereacross. That is, when spools 10 and 11 are freed for rotation, very little friction exists between web 19 and capstan 16. In this situation, web leaving spool 10 can slide over capstan 16 into chamber 14 with no web entering chamber 13. In magnetic tape handlers, this undesired action causes an inoperative situation requiring manual intervention.

The present invention teaches a modification of the above-described tape handler to prevent this untenable situation from occurring. Chambers 13 and 14 have a depth approximately equal to the width of web 19 and, as such, the pressure differential provided by vacuum source 17 makes the web appear as a piston causing it to enter the two chambers. According to the present invention, in addition to this piston effect, web 19 is also used as a valve during loading.

According to this invention, a fluid communication means extends through common wall 15 providing fluid communication between chambers 13 and 14. In FIG. 1, the fluid communication means comprises a pair of holes 30 extending through wall 15 immediately below capstan 16 and above magnetic

transducer 31. No other fluid communication connections are made to tubes 30. In some prior art configurations, a vacuum source was connected to tubes extending between the two vacuum chambers. However, the extra connection decoupled the fluid communication connection between chambers 13 and 14 and made such connections ineffective to provide the now-described valving operation in accordance with the practice of the present invention.

The combination of fluid communication means 30 and web 19 creates a valve for temporarily clamping web 19 against common wall 15 during loading operations such that the web 19 loads equally into both chambers 13 and 14. Assume, for purposes of discussion, that web 19 has loaded, as indicated by the solid line extending through chambers 13 and 14. At this time, the web 19 is pulled by vacuum from chamber 13 against common wall 15, as at 32. Since web 19 has a width equal to the depth of wall 15, and the holes 30 are less than the depth of wall 15, the web 19 blocks the vacuum flow between chambers 13 and 14. Web 19 no longer can slide over capstan 16 from spool 10 into chamber 14. The vacuum source then pulls web 19 into chamber 13 at least until it reaches the position indicated by dotted line 33. At this time, web 19 covers both ends of tubes 30, thereby removing the vacuum therefrom making it inoperative to clamp web 19 in either chamber. It is understood that web 19 may be loaded further into chambers 13 and 14, as may be desired.

During subsequent web handling operations, such as in a magnetic transducing operation (reading or writing), web 19 is kept in chambers 13 and 14 such that it always covers both ends of tubes 30. When this arrangement is maintained, tubes 30 are inoperative to affect movement of web 19.

Also of interest is the possibility of the web being removed from chamber 13 during web-handling operations. If this is the case, web 19 is again clamped against the wall 15 at area 32. If the reel 10 is activated to move web 19 toward capstan 16, the vacuum provided by source 17 may again reload web 19 into chamber 13, as above described.

In FIG. 2, a modification of the fluid communication means is shown. In this arrangement, slot 40 is formed in the front face 41 of common wall 15. Relating to FIG. 1, common wall face 41 is facing the viewer of the drawing. In this instance, a glass door 42 is hingedly secured to one side of the vacuum columns, such as at 43. During normal operation, door 42 is closed against the FIG. 1 illustrated assembly to complete web-receiving chambers 13 and 14, as is well known, and, as well, to close slot 40 to provide a fluid communication means extending between chambers 13 and 14.

In FIG. 3, single hole 44 is shown as constituting fluid communication means. This hole extends to the web-receiving chamber walls 45 and 46 without recess 47 illustrated in FIG. 1. It is understood that any form of fluid communication means may be provided so long as they extend between the chambers relatively close to capstan 16; that is, such that during normal web handling operations, the web always covers both ends of the fluid communication means.

If common wall 15 were an extremely thin wall, the fluid communication means could be a set of perforations extending through the wall. As shown in FIG. 1, transducer 31 is below fluid communication means 30. Since, in a magnetic tape handling operation, the transducer must be in continuous operative relationship to web or tape 19, it is seen that the fluid communication means will always be covered by the web during transducing operations. No limitation to the placement of the fluid communication means is intended. It could also be placed below transducer 31.

The fluid communication means need not extend directly between chambers, such as shown in FIG. 1. Alternately, the fluid communication with chamber 13 may be lower than in chamber 14, such as below transducer 31, or vice versa. Depending upon the type of loading and other design factors, the fluid communication between chambers 13 and 14 may be established for loading control in a myriad of configurations. Also, as used herein, the term "intermediate" is intended to

include connections made between chambers 13 and 14 either through common wall 15 or via a C-shaped conduit extending outwardly from web contacting surfaces 50 and 51, respectively, in chambers 13 and 14, that is, a fluid passageway opening through surfaces 50 and 51 and with no other openings.

While the invention has been particularly shown and described with reference to preferred embodiments thereof, it will be understood by those skilled in the art that various changes in form and details may be made therein without departing from the spirit and scope of the invention.

What is claimed is:

1. A web-handling device for a single elongated web, including in combination:

means defining first and second adjacent web-receiving chambers and having web-contacting surfaces, each chamber having a web-receiving opening for the web and a fluid therein,

web path means establishing a travel path between said chambers for the web receivable by both said chambers, pneumatic means in communicative relation with said chambers exhausting fluid therefrom such that said chambers have a lower pressure inside than outside said chambers, and

fluid communication means in said means defining said chambers for providing fluid communication between said chambers and only having openings through said web-contacting surfaces.

2. The device set forth in claim 1 wherein said web path means further includes a rotatable web-transporting member between said web-receiving openings, and having a web-engaging surface for frictionally engaging a web during loading such that web movement thereacross is somewhat inhibited but sliding movement of said web over said member possibly occurring at low web tensions, said web entering said chambers by said fluid exhaustion, such entry being subject to variations including entry of one chamber to the exclusion of the other chamber, said fluid exhaust from said other chamber acting through said fluid communication means to clamp said web to said fluid communication opening in said one chamber to inhibit further entry of said web thereinto and thereby facilitating entry of said web into said other chamber, and said fluid communication means inhibiting movement of said web over said member until the web has loaded into both chambers a predetermined amount, as determined by said fluid communication opening in said one chamber, at which time said web blocks said fluid communication means in both chambers to make it inactive.

3. A magnetic tape transport having the device set forth in claim 2 and further including a transducer in said first chamber, and

said fluid communication means establishing fluid communication from said second chamber to said first chamber intermediate said transducer and said web transporting member.

4. The transport set forth in claim 3 wherein said pneumatic means has a common communicative relation with said first and second chambers opposite said web-receiving openings such that both chambers have substantially the same lowered pressure therein.

5. The device of claim 2 with a common wall separating said chambers and wherein the chambers have a depth substantially equal to the width of the web to be received with the chamber depth extending along said common wall,

said fluid communication means having a dimension not greater than said web width along said web contacting surfaces in each chamber, and extending through said common wall.

6. The device of claim 5 wherein said fluid communication opening comprises a slot extending through said common wall between said web-contacting surfaces and further having a door closable against said common wall over said slot.

7. The method of loading an elongated web into first and second adjacent web-receiving chambers respectively having

first and second web contacting surfaces, the improvement including the following steps in combination:

- disposing an elongated web across web-receiving openings of said chambers,
- providing a pressure differential across said web for urging same into said chambers, 5
- establishing a vacuum clamp in said first chamber along said first web contacting surface dependent upon pressure in

the second chamber whenever said web has entered the first chamber a first distance and has not entered the second chamber along said second web contacting surface a second distance for clamping the web against further movement into said first chamber, and removing said clamp when the web has loaded into said second chamber said second distance.
